UNITED STATES PATENT OFFICE

2,004,051

APPARATUS FOR CONTINUOUSLY CLEAN-
ING RAILWAY BALLAST

Maurice Henri Lemaire, Paris, France

Application August 5, 1933, Serial No. 683,845
In France August 11, 1932

5 Claims. (Cl. 37—104)

The invention relates to an apparatus for carrying out continuously the stripping of railway tracks of their ballast, the cleaning of the ballast and the replacement of the rails on the cleaned ballast. The apparatus consists in essence of a long rigid beam mounted at its extremities on two bogies which run on the track itself to be treated and carrying at its middle part one or more excavators which pass under 10 the track while the latter is raised above the ballast. The ballast removed by the excavators is taken to a screen from which the cleaned material falls back between the sleepers of the track and is spread by an equalizing and levelling arrangement, and the combined apparatus advances continuously along the track while the excavators carry out their operations as if the rails and sleepers were not there.

Such a method was described in my Patent No. 1,899,874 and the present invention is directed to a new constructional form of the apparatus for putting this method into practice.

The new apparatus exhibits several characteristic features which will be mentioned in the following description and will be detailed herein-after.

The accompanying drawings illustrate the apparatus according to the invention and therein

Figure 1 is a longitudinal elevation of the apparatus complete,

Figure 2 is a transverse section of the excavator 1 taken on the line 1—1 of Figure 1,

Figure 3 is a transverse section of excavator 2 in travelling position taken on the line 2—2 of Figure 1,

Figure 4 is diagrammatic section similar to Figure 2 but with the buckets moved sideways,

Figure 5 is a plan on a larger scale of the part of the excavator operating under the track,

Figure 6 is a longitudinal section taken on the line 3—3 of Figure 5,

Figure 7 is a transverse section taken on the line 4—4 of Figure 5,

Figure 8 is a detail view showing parts of the buckets at the upper part of the excavator, and

Figures 9 and 10 show details in elevation and plan respectively of the roller guiding device for the track in operation on a curve.

As will be seen from the drawings the new apparatus comprises for example two excavators 1 and 2; the first is shown in operative position (Figures 1 and 2) while the second is shown in travelling position (Figures 1 and 3).

The ballast removed by the excavators is tipped 55 into the feeding hoppers of a belt conveyor 3

which takes the ballast to the rear to feed a belt elevator 4 with transverse flights which tips the material on to a vibrating screen 5.

The refuse and the dust are caught under the screen by another belt conveyor 6 and discharged either on to a conveyor 7 to load wagons behind the apparatus or on to a transverse conveyor 8 which deposits them beside the track.

The cleaned ballast is returned to the road by chutes 9 and is spread by a levelling and equalizing device 10 similar to those already described in the above-mentioned patent specification.

Each excavator can move as a whole in the following three ways:—

1. Vertical movement is provided to make it 15 possible to regulate the depth to which the ballast is removed by means of a structure 14 shown in Figure 1, which carries the excavator and slides vertically in a fixed frame 15 fast with the bracing of the beam P. The vertical movement of 20 the moving frame is carried out by an electric motor 16 actuating lifting screws 17 (Figs. 1 and 3) by means of worm reduction gear and bevel gear 18.

2. Transverse movement, that is to say in a 25 direction perpendicular to the track, is provided to permit the excavator to remain centred on the centre line of the track when working on a curve.

For this purpose each excavator is supported 30 on the frame 14 through the intermediary of a second structure 19 which is moved by means of a roller device on horizontal rolling tracks 20 (Fig. 4) carried by the structure 14.

The transverse movement is effected by a 35 hand-wheel 21 and transmitted by worm reduction gear and spur gears engaging a rack 22 fixed on the transverse frame 19 (Figs. 1 and 4).

3. Finally, the tension of the chain is ensured by an electric motor 23 (Fig. 2) driving two screw 40 spindles 24 which raise or lower the upper part of the excavator in relation to the complete transverse structure 19 by making it pivot about an axis 25 fixed to this structure (Fig. 2).

In accordance with the invention each excavator comprises two chains 11a, 11b, which carry buckets 11 (Fig. 2) each attached thereto by a lateral face and which are guided when passing under the track by two lateral chain guides 12 (Fig. 7) embracing the buckets and braced together to form a frame which supports two longitudinal sliders or skates 13, on which the sleepers of the track are supported (Figs. 2, 3, 5, 6 and 7).

This arrangement makes it possible to obtain an important new result which is the following. 55

If the excavator is raised or lowered vertically the track is raised or lowered to the same extent. The chain guides play a double part, firstly that of guiding the buckets under the track so as to obtain a flat road bed, and secondly to carry and lift the track in a continuous manner during the movement of the apparatus along the track, as the sleepers slide by their under surfaces on the skates carried by chain guides.

10 The arrangement of the chain guide frame which has just been described has the advantage of being simple and of making it possible to obtain in operation the minimum distance between the underside of the sleepers and the upper edge 15 of the buckets during the progress of the apparatus along the track without any risk of the buckets catching in the sleepers.

For a particular type of bucket working at a particular depth of cut there is thus obtained 20 the minimum height of lift of the track. Now, it is very important to reduce this height to a minimum for a given length of the apparatus between inner axles, i. e. those nearest each other to reduce the stresses to which the rails are subjected.

25 The bucket chains of the excavators are driven by two sprockets 26, (Figs. 1, 2, 3, 4) keyed on a shaft which receives its movement from an electric motor 27 by means of a power limiter and spur gears. They run at their lower part on 30 guide sprockets 28 (Fig. 2).

The buckets 11 have on their base at the forward side picks 29.

As the chains are subjected during operation to a combined movement of progress along the track due to the translation of the whole apparatus and rotation about the shafts 26 and 28, it results therefrom that the picks 29 engage a horizontal slide of ballast disintegrating it and directing it into the interior of the buckets and making it pass under the structure of the forward chain guide (Figs. 5, 6, 7).

40 The picks project beyond the forward part of the front chain guide (Fig. 7) in such a manner that a horizontal slice of ballast can be engaged over a height greater than the free space existing between the bottom of the chain guide and the bottom of the cut without the possibility of the ballast jamming in front against the chain guide or against the lateral face of the buckets.

50 This arrangement contributes to the possibility of reducing the raising of the track to a minimum for a given depth of cut.

55 As the buckets emerge beyond the track they pass in front of a shield 30 of cylindro-conical shape (Figs. 2, 5, 6) concave forwards, in such a manner that towards the front of the buckets there is a suitable space 31 between the buckets and the shield, and towards the rear of the buckets this space 32 is practically zero (Fig. 6).

60 The ballast which the buckets push in front of themselves arrives in the shield, rises along the shield partly flowing backwards so to fill the buckets completely over their whole length due to the conical form of the shield.

65 This arrangement makes it possible to construct an excavator of large output comprising buckets elongated in the longitudinal direction of the track and comparatively narrow, so that the ballast can be removed from the track in a comparatively thin layer with only a small height of lift of the track under the machine.

70 The reactions due to the forward movement of the buckets in the ballast are absorbed by rollers 33 with vertical axes (Figs. 5 and 7) mounted in 75 the rear chain guide.

The bottom 34 of the buckets is inclined as may be seen from Figure 8, and the buckets are so spaced that the emptying of the ballast from a bucket is made against the bottom of the preceding bucket. Due to the particular inclination of the bottom the ballast is guided into the charging hopper 35 of the belt conveyor.

This arrangement is particularly advantageous for obtaining an excavator of large output with closely spaced buckets at a high speed of rotation and nevertheless tipping the ballast within the chains at an angle of deflection suitable for the ballast to fall into the charging hopper situated vertically under the top sprocket (26) of the excavator.

10 There remains to be explained how the apparatus is put into operation and how it is set into position for travelling.

15 Each excavator has lateral arms 40 pivoted on axes 41 carried by the excavator frame. The lower extremities of these arms may be coupled to the chain guides 12 in the position of Figure 2.

To pass from the operating position, Fig. 2, to the travelling position, Fig. 3, the first operation is to cut the excavator chains into two portions as 25 may be understood from Figure 3. Then the arms 40 are raised so that the folded apparatus comes within the loading gauge G of the track (Fig. 3).

30 The raising of the arms 40 can be carried out automatically by means of chains 44, one extremity of which is fixed at 45 and the other extremity of which is attached at 42 to the arms 40. When the excavator is raised the chain 44 is pulled and causes the arms to pivot, bringing them back to the position shown in Figure 3.

35 The chain guides and the buckets located in the chain guides remain under the track until the resumption of operations. So as not to cause a loss of level in the profile along the track at the end of a period of work the precaution is taken before thus abandoning the chain guides to lower the excavator to its full extent to completely submerge the chain guides under the unraised track so that the track can resume its 40 position.

45 Moving to the operating position is carried out in the inverse manner.

It is obvious that at the commencement of an operation the chain guides and the corresponding part of the bucket chain are previously placed 50 under the track by any suitable means.

On curves the track is maintained in place, if it tends to become displaced, by an arrangement which can be pressed hard against the inner edge of the right hand or left hand rail according to 55 the direction of the curvature.

This arrangement comprises a roller 50 (Fig. 1). Figures 9 and 10 show the details of this arrangement. The roller 50 which presses against the inner edge of the rail 55 is mounted at the end of an arm 51 which can rotate about an axis 52 integral with the principal beam, the rotation of the arm about this axis being effected by a wheel 53.

60 The track is kept in its place by the simultaneous action of the rollers 49 integral with the excavator (Fig. 2) and by the roller 50.

65 It will be seen for example that the more the angle α (Fig. 10) diminishes the more the track is pushed sideways in the direction of the arrow.

70 The above arrangements are only given by way of example, the form, dimensions, materials employed and all detail arrangements may vary without altering the principle of the invention.

75 What is claimed is:

1. In an apparatus for cleaning railway ballast consisting of a beam moving along the track, track elevators carried by the said beam, endless excavators including chains and buckets surrounding the beam and the rails, improvements for increasing the output comprising track supports proper for guiding the excavator chains, implements integral with excavator buckets laterally thereof, a shield at the outlet of the excavation, the buckets each having an inclined bottom for deflecting during its discharge the ballast contained in the next bucket.
2. In an apparatus for cleaning railway ballast consisting of a beam moving along the track, track elevators carried by the said beam, endless excavators including chains and buckets surrounding the beam and the rails, improvements for increasing the output comprising rigid chain guides integral with longitudinal sliders on which the sleepers are supported, implements integral with excavator buckets laterally thereof, a shield at the outlet of the excavation, and the buckets each having an inclined bottom for deflecting during its discharge the ballast contained in the next bucket.
3. In an apparatus for cleaning railway ballast consisting of a beam moving along the track, track elevators carried by the said beam, endless excavators including chains and buckets surrounding the beam and the rails, improvements for increasing the output comprising track supports proper for guiding the excavator chains, picks carried by the excavators laterally thereof and directed towards the front in the direction of travel of the chain, a shield at the outlet of the excavation, and the buckets each having an inclined bottom for deflecting during its discharge the ballast contained in the next bucket.
4. In an apparatus for cleaning railway ballast consisting of a beam moving along the track, track elevators carried by the said beam, endless excavators including chains and buckets surrounding the beam and the rails, improvements for increasing the output comprising track supports proper for guiding the excavator chains, implements integral with excavator buckets laterally thereof, a shield at the outlet of the excavation, the buckets each having an inclined bottom for deflecting during its discharge the ballast contained in the next bucket, an arrangement with rollers integral with the beam, the rollers rolling against the inner edges of the rails of the track to be cleaned, and resilient means pressing the said rollers against the track.
5. In an apparatus for cleaning railway ballast consisting of a beam moving along the track, track elevators carried by the said beam, endless excavators including chains and buckets surrounding the beam and the rails, improvements for increasing the output comprising track supports proper for guiding the excavator chains, implements integral with excavator buckets laterally thereof, a shield at the outlet of the excavation, the buckets each having an inclined bottom for deflecting during its discharge the ballast contained in the next bucket, an arm pivoted to the truck between the bogies, and a roller at the end of the said arm and bearing against one of the rails of the track to be cleaned.

MAURICE HENRI LEMAIRE. 35
